DESIGN FOR A CONDIMENT HOLDER

Alfred J. Flauder, Nichols, Trumbull, Conn., assignor to The Weidlich Brothers Manufacturing Company, Bridgeport, Conn., a corporation of Connecticut

Application August 24, 1940, Serial No. 94,610

Term of patent 3½ years

To all whom it may concern:

Be it known that I, Alfred J. Flauder, a citizen of the United States, residing at Nichols, in the town of Trumbull, in the county of Fairfield and State of Connecticut, have invented a new, original, and ornamental Design for a Condiment Holder, of which the following is a specification, reference being had to the accompanying drawing, forming part thereof.

Fig. 2 is a side elevational view of the same, looking in the direction of arrow 2, Fig. 1.

Fig. 3 is a side elevational view of the same, looking in the direction of arrow 3, Fig. 1.

I claim:

The ornamental design for a condiment holder, as shown.

ALFRED J. FLAUDER.
